BOTTLE CASE

George Mordy, Pasadena, Calif.

Application February 17, 1941, Serial No. 379,243

6 Claims. (Cl. 217—19)

In the handling of bottled goods, especially such in the brewing and soft drink businesses, it is customary for empty bottles to be returned to the bottling plant in the cases in which they are distributed. Upon arrival the bottles must be removed from the cases by hand for cleaning, refilling, etc.

Consequently considerable hand labor is involved in the removal of these bottles from the cases and any attempt to empty the case all at once results in breakage of the bottles.

Accordingly it is one object of this invention to provide a case from which all of the bottles contained therein may be emptied in one operation, thus saving time and labor.

It is a further object of this invention to provide such a case in which the bottles in the removing operation are prevented from breaking.

It is a further object of this invention to provide such a case in which the bottles are normally supported by a bottom structure capable of shifting out of alignment with the bottles and thus permitting the dropping of the bottles through the case upon any desired unloading platform, belt or the like.

It is a further object of this invention to provide such a case which is simple, durable and economical of structure.

Further objects and advantages of this invention appear hereinafter.

In the accompanying drawing:

Fig. 1 is a plan view of a device embodying the invention.

Fig. 2 is a section taken on the line 2—2 of Fig. 1.

Fig. 3 is a section similar to Fig. 2 showing the case in position for emptying out the bottles.

Fig. 4 is a section taken on the line 4—4 of Fig. 1.

Referring more particularly to the drawing, I have illustrated a case 10 including the side walls 11 and end walls 12.

Disposed within the case 10 is the web 13, dividing the case into the conventional two dozen compartments by means of the lateral ribs 14 and transverse ribs 15. It will be appreciated that in practice the web 13 extends from slightly above the bottom of the case approximately one-half way up the case, though, if desired, the web may extend fully to the top of the case.

The end members 16 of the web 13 may be broken as at 17 to leave a space therebetween.

In each of the end walls 12, below the web 13, a slot 18 is provided. A bottom 19, composed of lateral ribs 20 and transverse ribs 21 is disposed

beneath the web 13 and having its end ribs lying in the slots 18.

A lever 22 is pivotally mounted, as by means of a pin 23 to the inner side of each side wall 12, and is so disposed that a part of said lever lies across the handle openings 24.

It will be observed that the bottom 19 is so constructed that the transverse ribs 21 lie directly below the transverse ribs 15 of the web 13 while the lateral ribs 20 are spaced apart the same distance as are the lateral ribs 14 of the web 13.

A pin 25 is provided upon each end transverse rib 21 adapted to be engaged by a slot 26 on the levers 22.

It will be noted that the bottom 19 is thus composed of a web structure similar to the web 13 and by reason of the slots 18 is slidably mounted so that it may be shifted, by means of the levers 22, either so that the lateral ribs 20 are disposed so as to support the bottles 27, as shown in Fig. 2, or so as to permit the dropping of the bottles through the webs, as in Fig. 3.

The bottom 19 is thin and the resulting fall when the bottles are dropped out is not sufficient to cause breakage of the bottles.

Suitable stops (not shown) may be provided in the slots 18 so that when the handle 22 is thrown as far as it will go from vertical, the bottom 19 will be in position to release the bottles and when the handle 22 is returned to vertical the bottom will be in closed position.

From the foregoing description it will be seen that I have provided a bottle case, in which the bottles may be placed and then, by simply shifting the handles 22 and lifting, the entire supply may be emptied therefrom in one operation.

While the particular forms of the invention herein described are well adapted to carry out the objects of the invention, it is to be understood that various modifications and changes may be made without departing from the principles of the invention, and the invention includes all such modifications and changes as come within the scope of the appended claims.

I claim:

1. In a bottle case of the type having a web portion dividing said case into a plurality of compartments, a bottom structure adapted to slide in grooves in the walls of said case, said bottom structure including lateral ribs spaced substantially equidistant to the lateral ribs of said web portion, and means for shifting said bottom structure from position where said lateral ribs of said bottom structure underlie said lateral ribs of said

web portion to position where said lateral ribs of said bottom structure lie across said compartments.

2. In a bottle case of the type having a web portion dividing said case into a plurality of compartments, a bottom structure adapted to slide in grooves in the walls of said case, said bottom structure including lateral ribs spaced substantially equidistant to the lateral ribs of said web portion, and a lever pivoted upon said case and engaging said bottom structure for shifting said bottom structure from position where said lateral ribs of said bottom structure underlie said lateral ribs of said web portion to position where said lateral ribs of said bottom structure lie across said compartments.

3. In a bottle case of the type having a web portion dividing said case into a plurality of compartments, a bottom structure adapted to slide in grooves in the walls of said case, said bottom structure including lateral ribs spaced substantially equidistant to the lateral ribs of said web portion, and a pair of levers pivoted upon said case and engaging said bottom structure for shifting said bottom structure from position where said lateral ribs of said bottom structure underlie said lateral ribs of said web portion to position where said lateral ribs of said bottom structure lie across said compartments.

4. In a bottle case of the type having a web portion dividing said case into a plurality of compartments, a bottom structure adapted to slide in grooves in the walls of said case, said bottom structure including lateral ribs spaced substantially equidistant to the lateral ribs of said web portion,

portion, and a pair of levers pivoted upon said case and engaging said bottom structure for shifting said bottom structure from position where said lateral ribs of said bottom structure underlie said lateral ribs of said web portion to position where said lateral ribs of said bottom structure lie across said compartments, and handle apertures in said case adjacent said levers whereby the hands of the operator may engage said levers and said handle apertures simultaneously.

5. In a bottle case of the type having a web portion dividing said case into a plurality of compartments, a bottom structure underlying said web portion and having a plurality of spaced ribs spaced apart substantially equidistant to the spacing of one set of parallel walls in said web portion, said spaced ribs adapted in bottle discharging position to lie substantially directly beneath said parallel walls and in bottle supporting position to lie across said compartments.

6. In a bottle case of the type having a web portion dividing said case into a plurality of compartments, a bottom structure underlying said web portion and having a plurality of spaced ribs spaced apart substantially equidistant to the spacing of one set of parallel walls in said web portion, said spaced ribs adapted in bottle discharging position to lie substantially directly beneath said parallel walls and in bottle supporting position to lie across said compartments, and means engageable by the hand of an operator for moving said bottom structure from one position to another.

GEORGE MORDY.
